Application April 10, 1951, Serial No. 220,283

10 Claims. (Cl. 66—43)

This invention relates to hosiery knitting machines and methods. More specifically, it is concerned with circular knitting machines of the type disclosed in U. S. Patent #2,217,022 granted to R. H. Lawson and Isaac H. C. Green on October 8, 1940, characterized by having main and auxiliary knitting stations, respectively with plural interchangeable yarn feeds and with duplicate needle selecting mechanisms, and devised for the commercial production of fancy seamless stockings or socks with solid color design areas of large diamond or other configuration by reciprocatory or oscillatory operation of the needle cylinders. Incident to the knitting of ornamented stockings or socks by such machines, long floats are created as a result of introduction and withdrawal of contrastingly-colored yarns at the beginning and completion of the design areas. These floats extend crosswise of the interiors of the tubular fabrics, and in subsequently finishing the stockings or socks, must be cut close to the inner face of the fabric. In order to prevent the cut float ends from reeveing out of the fabric when the stockings or socks are drawn over the feet by the wearers, it has been necessary heretofore to tie said ends together by hand. This tying or knotting is time consuming and necessitates the employment of specially skilled help, thereby adding very considerably to production costs.

The chief aim of our invention is to obviate the above mentioned drawbacks. This objective is realized in practice, through provision of automatic means in connection with machines of the type referred to, suitable for carrying out our new method of knitting whereby the yarns are incorporated in the fabric in such a way at the regions of withdrawal that the float ends, after being cut, are effectively anchored against the possibility of subsequent pulling or reeveing out. As hereinafter more fully set forth, the purpose of our invention is achieved by starting and finishing the design areas or figures with a few needles, feeding the patterning yarn to these needles at one of the two knitting stations without there knitting it, and causing said needles to be actuated later at the other knitting station so that a yarn fed at the later station is knitted with the patterning yarn by one or more of the needles of the selected group in the initial and final courses of the design areas or figures.

Other objects and attendant advantages will appear from the following detailed description of the attached drawings, wherein Fig. 1 shows the top plan view of a circular hosiery machine line that of the Lawson et al. patent supra, modified in accordance with our invention for the practice of our improved method of knitting.

Fig. 2 is a fragmentary view showing the machine in front elevation.

Fig. 3 is a fragmentary view of the machine in end elevation, looking as indicated by the angled arrows III—III in Fig. 2.

Figs. 4 and 5 are diagrammatic views of the needles and the knitting cams of the machine in linear development, and respectively showing the relative positions of the needles and the cams during the formation of the initial and terminal course of a design area in accordance with our invention.

Figs. 6 and 7 are fragmentary views corresponding to Figs. 4 and 5, showing how the needles to which the patterning yarn is fed at the auxiliary station are actuated at the main station in the formation of the first and last courses of an ornamental area.

Fig. 8 is a perspective view of a fancy sock produced in accordance with our invention.

Fig. 9 is a fragmentary view of the fabric within the confines of the rectangle IX in Fig. 8 showing the inter-loopment at the beginning of the design area; and

Fig. 10 is a fragmentary view of the fabric within the confines of the rectangle X in Fig. 8 showing the inter-loopment at the completion of the design area.

As in the patent supra and as illustrated in Figs. 1—5, the basic machine includes a needle cylinder 3 which is supported for rotation and oscillation in a stationary bed 2. At auxiliary station designated A is a plurality of interchangeable yarn feeds 80 and a set of knitting cams comprising, as shown in Figs. 4 and 5, a pair of stitch cams 54, 55, a center cam 56, and an overlying guard or wing cam 57. The stitch cams 54 and 55 are mounted on a retractable block 51 (Fig. 2) which is slidably radially of cylinder 3 on a plate 52 supported by a fixed post 53. The block 51 is retractable by means actuated from a rotary cam drum (not shown) on timing shaft 97 as in the patent, the use of auxiliary stitch cams 54 and 55 being not required during rotary knitting phases of the machine. At the main station M is a similar series of interchangeable yarn feeds 81, and also a set of knitting cams comprising a pair of spaced stitch cams 63, 64, and a center cam 65. Selection of the feeds 80 at station A is effected, through individually associated levers 108, under a control of a drum 140, and the feeds 81 at the station M similarly through levers 92 under control of another drum 141. The drums 140 and 141 are centrally mounted respectively on transverse shafts 124, 125 journaled in bearing brackets 130, 132 and 127, 133 at opposite sides of needle cylinder 3. Through the medium of bevel gears 134, 135 and 136, 137, rotary motion is communicated to shafts 124, 125 from a shaft 44 which extends horizontally across the back of the machine, and which is journaled adjacent its opposite ends in rearward extensions of the brackets 126, 127. Shaft 44 is continually driven and turned through a complete rotation for each oscillatory stroke of the cylinder. Affixed to the shaft 124 immediately beyond opposite sides of drum 140, are supplemental rotary cams 270 and 275 whose functions are fully described in the Lawson et al. patent. At the station A, needles are selected in changing numbers for patterning under control of the drum 245 before they reach the auxiliary knitting cams during clockwise oscillations of the needle cylinder, and under control of a drum 301 during counterclockwise oscillations of said cylinder. At station M the drums 224 and 300 are similarly operated respectively during counterclockwise and clockwise oscillations for an analogous purpose. During the pattern knitting, the drums 224, 245, 300 and 301 are intermittently rotated by racking means controlled from the timing mechanism of the machine, each of them through a complete revolution for each pattern figure. In adapting the machine for the purposes of our invention, the stitch cams 54 and 55 at the auxiliary station A are mounted in their supporting block 51 with capacity for independent withdrawal radially of the needle cylinder 3. By means of horizontal links 530 and 531, outward shank projections 54' and 55' of the stitch cams 54 and 55 are connected respectively to the bottom ends of levers 532 and 533 which are fulcrumed on and independently shiftable longitudinally of a transversely-arranged non-rotating shaft or rod 535. At its opposite ends, the rod 535 is secured in blocks 536 and 537 screwed fast to the tops of the bearing brackets 130, 132 at auxiliary station A. As shown in Figs. 1 and 2, the levers 532 and 533 have horizontal finger projections 532' and 533' which are disposed outwardly of the end cam disks 274 and 271 of drums 270 and 275 on shaft 124, and are subject to actuation by cam projections 538, 539 respectively affixed to the exposed side faces of said disks. The springs indicated at 540 and 541 in Figs. 1 and 3, tend to urge the levers 532 and 533 inwardly for placement of their finger projections 532' and 533' into the paths of the cam projections 538 and 539. Normally, the levers 532 and 533 are held retracted by vertically-arranged control levers 542 and 543 which are medially fulcrumed on bearing projections 545 and

546 affixed to the brackets 130 and 132. As best shown in Fig. 3, the control levers 542 and 543 are provided at their tops with hook portions which overreach and engage behind the finger portions 532' and 533' of levers 532 and 533. Adjustable in the lower ends of levers 542 and 543 are screws 547 and 548 which are engaged by horizontally disposed angular levers 549 and 550. These angular levers 549, 550 are swingable about studs at the tops of posts 551 and 552 upstanding from the bed 2 of the machine, and have finger projections 549', 550' in engagement with the peripheries of special disks 555 and 556 at the tops of the drums 301 and 245 of the needle selecting mechanism at the auxiliary station A. The disks 555 and 556 are respectively provided with single notches 557 and 558 into which the finger projections of the levers 549 and 550 enter at certain times as will be explained later. At other times in a knitting cycle of the machine, it is necessary that actuation of the lever 533 from the drum 245 be prevented. Accordingly, for this purpose we have devised a lock-out means including a bell crank lever 559 (Figs. 2 and 3) which is pivoted at 560 on bracket 132, with its upright extremity engaging the bottom end of lever 533. The horizontal extremity of bell crank lever 559 is connected by a drop link 561 to an extension 562 at the swinging end of lever 282, which is actuated, in turn, through a thrust rod 284 from the timing drum 96 on the main cam shaft 97 of the machine. It is to be understood that in accordance with our invention, the drums 224, 245, 300 and 301 are so set up as to determine the selection of several needles, for example three, for the beginning and ending of each design area.

Operation

Let it be assumed that the top T of the stocking in Fig. 8 has been knitted to the course 508 by continual rotation of the cylinder 3 in the usual way from a gray yarn 510 (Fig. 9) fed from one of the main feeds 81 lowered in delivery position, with all of the needles actuated by the knitting cam 63 (Fig. 4) at station M, while the block 51 supporting the auxiliary knitting cams 54, 55 at station A is held retracted, and while the patterning controls are idle. In preparation for the knitting of the next fabric course 509 by the first oscillation of the needle cylinder 3 for patterning, cam block 51 is moved inward and drum 245 is picked to select three needles n^1 , n^2 and n^3 for elevation to yarn taking level at station A. At the same time, drum 301 is picked to advance the notch 557 in the top disk 555 for entry thereinto of the finger projection of lever 549 and thereby allow shifting of the lever 532 longitudinally of shaft 535 into the range of the cam piece 539 on cam disks 274 by the spring 540. By rotation of the shaft 124, cam piece 539 is brought into engagement with lever 549 to withdraw auxiliary stitch cam 54. Thus upon the first patterning oscillation of cylinder 3 in the direction of the arrow in Fig. 4, the butts of the three selected needles n^1 , n^2 and n^3 will follow the path indicated in dotted lines, over-riding auxiliary stitch cam 55 and by-passing retracted auxiliary stitch cam 54, and taking the black yarn 503' without knitting it. In continuing on, the needles n^1 , n^2 and n^3 will ride over main stitch cam 64 as in Fig. 4 and be depressed as in Fig. 6 with the remaining needles n to stitch drawing level by main stitch cam 63 after receiving a gray yarn 511 from a second feed 81 introduced at station M. Accordingly, the black patterning yarn 503' is knitted with the gray yarn 511 in plating relation by the three selected needles as at the loops l^1 , l^2 and l^3 (Fig. 9) in fabric course 509, yarn 510 having been withdrawn at the needle n^1 . At the beginning of the next or reverse oscillation of the cylinder 3, the drum 301 is picked to cause addition of another needle to the selected group, and also the notch 557 in the top disk thereof is advanced beyond the finger projection 549' of lever 549 for re-insertion of auxiliary stitch cam 54. Therefore, the selected needles will be actuated this time by auxiliary stitch cam 55 to knit the black yarn 503'. From then on, the machine will function in the manner disclosed in the Lawson et al. patent with attendant variant selection of needles as required for the patterning, with formation of interconnected selvage loops between the contrasting yarns at the boundary edges of the design area B, except at the knitting of the last design course as will be later explained. Of course, during the formation of the orna-

mental area B, the gray yarn 511 is introduced and withdrawn during each oscillation of cylinder 3, also as in the patent. As a consequence of interknitting of the black yarn 503' with the gray yarn 511 in the loops l^1 , l^2 and l^3 in course 509, the cut end E^1 of the float of yarn 503' will be effectively anchored in the fabric against pulling out subsequently. The cut end E of the float of yarn 510 will be likewise effectively anchored in turn by virtue of its being locked in by the double loop l^3 of yarns 503' and 511 at the point of reversal of the latter yarn in course 509.

At the beginning of the final patterning oscillation of the cylinder 3 for the formation of the last course 560 of the ornamental knitting, the notch 558 in the top disk 556 of drum 245 will be advanced by the last pick of said drum for entry thereinto of the finger end 550' of lever 550 which will thereby be actuated to withdraw auxiliary stitch cam 55. Under these conditions the butts of the same three needles n^1 , n^2 and n^3 which were used at the beginning of the patterning will follow the dotted line path in Fig. 5, i. e., overtravel auxiliary stitch cam 54, by-pass retracted auxiliary stitch cam 55 and take the black yarn 503' at station A without knitting it. But upon reaching station M, the needles n^1 , n^2 and n^3 will be depressed along with the remaining needles N by main stitch cam 64. However, this time, by reason of reversal of the yarn 510 at the needle n^1 at station M as in Fig. 7, said yarn will be knitted with the yarn 503' on said needle with resultant formation of a double loop at 14 in Fig. 10. Accordingly at this time, the yarn 503' only will be knitted into single loops l^5 and l^6 by the needles n^2 and n^3 . As the next course 561 of the fabric is knitted, the float end E^2 of yarn 503' will be locked in the sinker wale loop at l^7 and thus effectively held against pulling out; while the cut end E^3 of yarn 510 will be securely anchored in the double loop l^4 .

It is of course to be understood that during the knitting of the design figure B as hereinbefore described, a similarly shaped figure of the same or of a different color is concurrently knitted at the back of the stocking by variant selection of patterning needles in the manner set forth in the Lawson et al. patent. Likewise, as in the reference, the patterning may be continued downward of the leg portion of the stocking as well as downward of the instep if desired. In any case, through our invention, the cut float ends of the yarns will be so anchored in the fabric as to resist subsequent displacement when the stocking is drawn over the foot by the wearer. The laborious and costly tying together of loose yarn ends, as was heretofore necessary, is thus entirely eliminated.

Our invention is of course not to be considered as limited to the precise details of construction and arrangement herein shown and described herein by way of example, since these are subject to variation within the scope of the broader of the appended claims, as will be readily understood by those schooled in the knitting arts. The expressions "main" and "auxiliary" in connection with the two knitting stations were used merely for convenience of distinction. It is therefore to be understood that the improved mechanism may be duplicated at the main station or installed at the latter instead of at the auxiliary station if desired or deemed advantageous.

Having thus described our invention, we claim:

1. In a circular knitting machine, an oscillatable needle cylinder; a main knitting station with stitch cam means, a pair of yarn feeds, and means for selectively inserting and withdrawing the feeds; an auxiliary station circumferentially spaced from the main station and provided with stitch cam means; a pattern yarn feed and means for inserting and withdrawing the pattern yarn feed during each oscillation; means for selecting and elevating varying numbers of needles before they reach the auxiliary station incident to successive oscillations of the cylinder in opposite directions to receive the patterning yarn; and means operative at the beginning of the first oscillation of the cylinder at the initiation of the patterning to retract the auxiliary stitch cam means and so prevent actuation of a group of selected needles to which the patterning yarn is fed at the auxiliary station so that said yarn is not knitted until later in said first oscillation together with a yarn fed to the selected and to others of the needles at the main station, through actuation of the needles by the main stitch cam means.
2. In a circular knitting machine, an oscillatable needle

cylinder; a main knitting station with stitch means; a plurality of yarn feeds, and means for selectively inserting and withdrawing the individual feeds during each oscillation; an auxiliary station circumferentially spaced from the main station and provided with auxiliary stitch cam means, a pattern yarn feed and means for inserting and withdrawing the pattern yarn feed during each oscillation; means for selecting and elevating varying numbers of needles before they reach the auxiliary station incident to successive oscillations of the cylinder in opposite directions to receive the patterning yarn at the latter station; and means operative at the beginning of the last oscillation of the cylinder at the completion of the patterning to retract the auxiliary stitch cam means and so prevent actuation of the group of needles then selected and to which the patterning yarn is fed at the auxiliary station so that said yarn is not knitted until later in said last oscillation through actuation of said needles by the stitch cam means at the main station.

3. In a circular knitting machine, an oscillatable needle cylinder; a main knitting station with stitch cam means, a pair of yarn feeds, and means for selectively inserting and withdrawing the feeds; an auxiliary station circumferentially spaced from the main station and provided with auxiliary stitch cam means, a pattern yarn feed, and means for inserting and withdrawing the pattern yarn feed during each oscillation; means for selecting and elevating varying numbers of needles before they reach the auxiliary station incident to successive oscillations of the cylinder in opposite directions to receive the patterning yarn at the latter station; and means operative at the beginning of the first and last oscillations respectively of the needle cylinder at the initiation and completion of the patterning to retract the auxiliary stitch cam means and so prevent actuation of the group of needles then selected and to which the patterning yarn is fed at the auxiliary station, so that said yarn is not knitted until later in said respective oscillations at the main station by actuation of said selected needles by the stitch cam means at the latter station.

4. A circular knitting machine according to claim 3, wherein the auxiliary station is provided with a plurality of yarn feeds, and means for selectively withdrawing and inserting such feeds during successive oscillations of the needle cylinder.

5. In a circular knitting machine, an oscillatable needle cylinder; a main knitting station with a pair of spaced stitch cams, plural yarn feeds and means for selectively inserting and withdrawing the feeds during successive oscillations; an auxiliary knitting station circumferentially spaced from the main station likewise with a pair of spaced stitch cams, plural yarn feeds and means for selectively inserting and withdrawing such feeds during successive oscillations; and means operative during an oscillation of the cylinder in one direction, to withdraw one of the auxiliary stitch cams; and means operative during an oscillation of the cylinder in the opposite direction, to retract the other auxiliary stitch cam.

6. A circular knitting machine according to claim 5, wherein the means for actuating the feeds at the auxiliary station includes a horizontally-arranged shaft with rotary cam drum thereon; and wherein the means for retracting the auxiliary stitch cams includes pivoted fingers with link-connections to the respective auxiliary stitch cams, cam projections on the drum for acting upon the respective fingers, and means for moving the fingers

into and out of the path of the cam projections on the drum.

7. In a circular knitting machine, an oscillatable needle cylinder; a main knitting station with a pair of spaced stitch cams, plural yarn feeds, and means for selectively inserting and withdrawing the feeds during successive oscillations; an auxiliary knitting station circumferentially spaced from the main station, likewise with a pair of spaced stitch cams, plural yarn feeds, and means for selectively inserting and withdrawing such feeds during successive oscillations, the latter means including a horizontally-arranged shaft with a rotary cam drum thereon, pivoted fingers with link connections to the respective auxiliary stitch cams, and cam projections on the drum for actuating the respective fingers; needle selecting means including intermittently rotated pattern drums adjacent opposite sides of the auxiliary station; and means controlled by the pattern drums for moving said fingers into and out of the path of the cam projections on the auxiliary yarn feed actuating drum.
8. In a circular knitting machine, an oscillatable needle cylinder; a main knitting station with a pair of spaced stitch cams, plural yarn feeds and means for selectively inserting and withdrawing the feeds during successive oscillations; an auxiliary knitting station circumferentially spaced from the main station likewise with a pair of spaced stitch cams, plural yarn feeds, and means for selectively inserting and withdrawing such feeds during successive oscillations, the latter means including a horizontally-arranged shaft with a rotary cam drum thereon, pivoted fingers with link connections to the respective auxiliary stitch cams, and cam projections on the drum for actuating the respective fingers; needle selecting means including intermittently-rotated needle-selecting pattern drums adjacent opposite sides of the auxiliary station; and means controlled by the pattern drums for moving said fingers into and out of the path of the cam projections on the auxiliary yarn feed actuating drum, including medially fulcrumed levers connected with the fingers; vertically-arranged medially-pivoted arms each with one end engaging the corresponding pattern drum and with the other end engaging the opposite end of the corresponding lever.

9. A circular knitting machine according to claim 4, wherein the fingers are axially slidable on a fixed rod and urged toward the cam projections on the auxiliary feed control drum, and wherein the levers are respectively provided with adjustable screws for contact with the contiguous ends of the arms actuated by the pattern drums.

10. A circular knitting machine according to claim 7, provided with a timing drum; and further including lock-out means actuated from the timing drum and operative upon one of the levers to prevent release of the corresponding finger during continuous rotation of the needle cylinder prior to and after patterning cycles by cylinder oscillation.
